(57) **CLAIM**

The ornamental design for a portable high-resolution X-ray imaging device as shown and described.

DESCRIPTION

FIG. 1 is an upper perspective view of the portable high-resolution X-ray imaging device according to my design. FIG. 2 is a lower perspective view thereof;

FIG. 3 is a front elevation view thereof.

FIG. 4 is a back elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an exploded partial perspective view of an isolated portion of FIG. 1. The broken lines are optional features, including surface indicia, universal connectors, screw holes, and unclaimed portions. The features in broken lines form no part of the claimed design.

In the drawings, the dash-dot broken lines are for the purpose of illustrating portions of the portable high-resolution X-ray imaging device that forms no part of the claimed design. In FIGS. 1 and 9, the dash-dot broken lines are boundary lines of an exploded partial view that forms no part of the claimed design.
